UNITED STATES PATENT OFFICE.

HARRY W. HILL, OF BELOIT, WISCONSIN.

PULLEY-BEARING.

SPECIFICATION forming part of Letters Patent No. 337,953, dated March 16, 1886.

Application filed March 23, 1885. Serial No. 159,775. (No model.)

To all whom it may concern:

Be it known that I, HARRY W. HILL, a citizen of the United States, residing at Beloit, in the county of Rock and State of Wisconsin, have invented certain new and useful Improvements in Pulley-Bearings, of which the following is a specification, reference being had therein to the accompanying drawings.

10 My invention relates to improvements in removable pulley-bearings formed of two halves connected together; and the object of my improvements is to provide means for connecting these bearings with set collars and sleeves to facilitate the rebabbitting or renewal thereof.

The invention will first be described in connection with the drawings, and then be pointed out in the claims.

20 In the drawings, Figure 1 is a vertical section of a pulley with its loose sleeve or removable bearing and set-collar in elevation and mounted upon a shaft. Fig. 2 is a front view of the set-collar. Fig. 3 is a front view 25 of the hub of the pulley and its loose sleeve. Fig. 4 is a side view of the loose sleeve retained between the two halves of the set-collar. Fig. 5 is a front view of one part of the set-collar, and Fig. 6 the other part of the 30 set-collar. Fig. 7 is a longitudinal section of the detachable parts shown in Fig. 4.

In said drawings, A represents a sleeve or removable pulley-bearing split lengthwise or formed of two halves, and provided with 35 circular bosses A' at each end and circular bosses A² between them. Through this segmental sleeve the shaft B passes, upon which it revolves with the pulley wheel or gear carried thereby. On said shaft and adjoining

40 the end boss, A', is located a set-collar composed of two parts, C and C', as shown in Fig. 1. The part C is provided with side projections or bosses, c, and spaces c² on the inner side thereof, to engage with a similar 45 face on the part C'. In its capacity of set-collar, C is secured to the shaft B by means of a set-screw, C², which passes therethrough. The projections or bosses c and c' fit snugly 50 in the spaces c² and c³, so that the parts C C' revolve together with the shaft B, and there

is thus no wear of their eye, which would be the case if these were allowed to revolve loosely on the shaft.

The pulley-wheel D, as shown in Fig. 1, is firmly secured to the circular bosses A² of the 55 sleeve A by means of set-screws d passing through the hub D' at its outer ends. The sleeve A or removable pulley-bearing is made in two parts or halves, to facilitate the renewal of its bore when used with loose pulley-wheels, gears, &c., as they become much 60 worn in course of time by reason of the shaft revolving loosely therein, deranging their alignment and central position to said shaft, necessitating throwing aside comparatively 65 good pulley-wheels, &c., and replacing them at considerable expense with new ones.

My split sleeve A and the means to retain its parts together are designed to reduce this expense, inasmuch as being in two parts it 70 can be easily taken out of a pulley, wheel, gear, &c., without taking down or in any way disturbing the shafting; and if babbitted, the old or worn babbitt can be readily taken out, the two parts being placed together on 75 the shaft, as shown in Fig. 4, with the two parts C and C' of the set-collar separated sufficiently to receive the removable pulley-bearings or sleeve A between them, and the side projections, c and c', being fitted inter- 80 nationally to receive the externally finished or turned rings or circular bosses A' on each end of the removable bearing A. It is evident that if both ends of said bearings are inserted into and between the dental projections c and c' or bosses of C and C' the hub or sleeve A 85 will be held exactly central to and in line with its shaft.

If babbitt be poured into each half of the sleeve A at holes or perforations a, the bore 90 of the sleeve A will be perfectly and cheaply renewed.

In Figs. 4 and 7 the two parts C and C' of the set-collar are shown separated, or one at each end of the sleeve A, and the latter re- 95 tained in position to be babbitted.

Having now fully described my invention, I claim—

1. The combination of the removable pulley-bearing A, formed of two segmental parts, 100

with collars secured to the shaft thereof and designed to inclose the periphery of the ends of said segmental parts, substantially as and for the purpose described.

5. 2. The combination of the removable pulley-bearing A, formed of two segmental parts, with collars C and C', provided with side projections adapted to receive the ends of said bear-

ing, substantially as and for the purpose described. 10

In testimony whereof I affix my signature in presence of two witnesses.

HARRY W. HILL.
